SKIN CLAMP

Martin T. Lawlor, Waterbury, Conn., assignor, by
mesne assignments, to Irving Rossi

Application January 20, 1944, Serial No. 518,928

15 Claims. (Cl. 85—5)

1

The present invention relates to skin clamps or fasteners of the type serving as temporary rivets for assembling perforated members in aligned position, such as sheets or plates, preparatory to a riveting or like operation.

In the co-pending patent applications filed by Peter F. Rossmann, Serial No. 384,461, dated March 21, 1941, entitled "Clamping device," and Serial No. 441,153, filed April 30, 1942, entitled "Fasterner," now Patent No. 2,354,480, there is described a clamp of this character comprising substantially a housing or body having a work engaging base provided with an opening of a diameter substantially equal to the perforations in the aligned plates or other work to be assembled. A retainer comprising a pair of resilient legs having shoulders at their outer ends and operable towards each other is arranged to slide through said opening, a spreader arranged in fixed relation to said body being interposed to space said legs apart. The retainer is urged inwardly of said body into retracted or clamping position by means of a coil spring interposed between its inner end and said body, whereby to cause said shoulders to engage the outer surface of said base in the non-operative position of the device or to resiliently clamp the perforated sheets or other work between said shoulders and said base in the operative or use position of the device.

The clamp is applied to and removed from the work by compressing the spring by the aid of a suitable tool such as a plier applied to the housing and the inner end of the retainer, whereby to cause the legs to project outwardly of the body beyond said spreader in such a manner as to approach each other or flex sufficiently to enable their insertion through and removal from the perforations.

Clamps of this type are required in considerable numbers, in particular in the manufacture of airplanes, to assist in the riveting of the metal sheets or skins to the structure of the planes, in locating lock or stop nuts in proper position for securing them to a cowling or other metal structure and other applications.

Practice has shown that in order to insure safe riveting of the sheets, considerable clamping forces are required to prevent misalignment of the sheets or plates during the riveting operation and other drawbacks. This makes it necessary to employ heavy clamping springs which in turn require a substantial force to be exerted by the pliers or other tools during the insertion and removal operations, resulting in considerable

2

stresses to which the clamps have to be subjected in use.

As a result thereof, it has been experienced that the clamps may fly apart when parts thereof become accidentally damaged during use, in particular when the heads or shoulders of the retainer are accidentally sheared or broken off. This may result in serious accidents and danger to the workmen in the neighborhood, as is understood.

An object of the present invention is therefore, to improve the safety factor of clamps of this type by preventing the parts to be ejected forcibly if one of the elements becomes accidentally damaged or broken.

A further object is to provide a clamp of this type, which is both simple in construction and efficient in operation and which can be easily and safely installed and removed from the work without complicated tools or special operations.

Further objects and aspects of the invention will become more apparent from the following detailed description taken in reference to the accompanying drawing forming part of this specification, and wherein:

Figure 1 is an elevation, partly broken away, of a clamp embodying the principles of the invention; Figure 2 is a side view shown partly in cross-section, of the clamp according to Figure 1; Figure 3 is a cross-section taken on line 3—3 of Figure 2; and Figure 4 is a cross-section taken on line 4—4 of Figure 1.

Like reference characters identify like parts in the different views of the drawing.

The clamp shown comprises a cup or thimble-shaped body or housing 10 having a flange 11 at its open end and a sheet engaging bottom or base 12 provided with a central bore or opening 13. The latter has a diameter substantially equal to the diameter of the perforations in the work to be assembled such as two superposed perforated plates A and B shown for illustration in the drawing.

A plunger or retainer comprising, in the example shown, a member of U- or hairpin shape having a pair of resilient legs 14 provided with projections, or shoulders 15 at their outer ends, is arranged to slide through the opening 13 in the body 10 with said legs being held in spaced apart position by the depending portion 16 of a substantially T-shaped spreader interposed between said legs and having a cross-arm 17 resting against the inside of the bottom or sheet engaging base 12. A cap or inverted cup-shaped washer 18 is placed over the spreader cross-arm 17 to

provide a recess for the latter, said washer having a central opening for passing the legs 14 and being provided with diametrical recesses in its cylindrical portion as indicated at 17' and adapted to receive the ends of the cross-arm 17, whereby to lock the spreader against or prevent relative movement with respect to said washer. Alternatively, the spreader cross-arm 17 may be mounted loosely within the recess provided by the spreader 18.

In the example illustrated, the legs 14 which are preferably constructed from a single length of wire of half round or segmental cross-section, have inner parallel portions 14a followed by intermediate portions 14b and outer portions 14c which may be bent inwardly as shown in the applications mentioned above so as to approach each other by their own spring tension when the legs are projected beyond the spreader 16 by compression of the spring 20 during the insertion and removal operations. Alternatively, the lower portions 14c may be substantially parallel or normally spaced similar to the portions 14b and adapted to flex sufficiently to allow insertion through and removal from the sheet perforations.

The purpose of the washer 18 is to locate the spreader to prevent canting thereof and to serve as a base for a coiled clamping spring 20 encircling the legs 14 and having its lower end engaging said washer and having its upper end engaging the inner end of the retainer. In this manner, the washer 18 acts both as a balancing means for the fastener, while at the same time taking the thrust of the spring away from the spreader arm 17 as well as from the housing 10, resulting in a favorable distribution of the forces exerted by the spring without producing excessive stress on the parts and preventing the legs and spring from bending sideways or canting in the manner pointed out. This in turn enables the size of the parts and the clamp to be held at a minimum.

The washer 18 may be omitted if a weaker spring is used, sufficient in some cases, in which case the lower end of the spring engages the spreader cross-arm 17 and in this manner prevents the spreader from moving in the longitudinal direction by maintaining it in bearing engagement with the inside of the bottom or base 12.

In order to further improve the symmetry or balance of the clamp, there is provided a cylindrical sleeve 21 interposed between the legs 14 and the spring 20, said sleeve having an upper flange or shoulder 22 engaged by the upper end of the spring and terminating in an outwardly flaring skirt or rim 23 secured to or engaging the head or cap 24 secured to the inner end of the legs 14. Cap 24 for this purpose has an inwardly flaring skirt 24' engaging the skirt 23 of the sleeve 21. The cap in the example shown is secured to the legs 14 by means of a pin 25 passed through a lateral opening in the cap, said pin fitting snugly within the upper bent portion of the legs 14 and being secured or held in place by staking or deforming the cap or in any other suitable manner. The sleeve 21 advantageously has a close fit within the coil spring and the legs 14 to obtain an optimum straightening or balance of the entire retainer unit comprising the parts 14, 21, 24 and 25 within the spring 20.

In use, spring 20 is compressed by applying a suitable tool such as a plier having jaws or sockets engaging the outer surface of cap 23 on the

one hand and the flange 11 on the other hand. During compression, the legs will slide beyond the spreader 16, whereby to cause sections 14c and shoulders 15 to approach each other or to flex sufficiently to enable their insertion through and removal from the perforations in the plates A and B or other work to be assembled.

The housing and remaining elements may be hardened to withstand the stress and forces exerted thereon and to reduce the size of the clamp to a minimum. Sleeve 21 may consist of brass and may have a length designed to act as a stop to limit the compression of the spring when the lower end of the sleeve engages the washer 18.

In a clamp of this type intended for many thousands of insertion and removal operations, it may happen that due to wear and other causes, the parts, in particular the projections or shoulders 15, may be damaged or broken away, in which case the spring and/or retainer will be ejected forcibly or fly apart haphazardly, where-to involve serious danger and operator hazard.

According to the present invention, this drawback is avoided and adequate operating safety insured by locking or anchoring the spring 20 to the body or housing 10 on the one hand and to the retainer on the other hand, in such a manner, that, with the spring becoming suddenly relaxed from the compressed to its expanded position due to damage or breakage of one of the parts, in particular the shoulders or projections 15, both the spring or any of the other remaining parts will be prevented from being ejected forcibly or flying apart and endangering workmen in the neighborhood.

For this purpose, at an intermediate part of the housing 10, a plurality of preferably equally spaced nubs or inward projections 26 are struck in position, so that they will at least inter-engage one or more turns at the inner end of the spring 20 adjacent to the spreader 17 and washer 18. Furthermore, at the opposite end of the device the sleeve 21 has its side walls diametrically skived or punched as shown in 27 leaving two connecting straps or projections 28. The latter, after the spring has been assembled against the flange 22 of the sleeve 21, are collapsed or folded outwardly back upon themselves to provide nubs or outward projections inter-engaging between two turns at the opposite end of the spring 20 and holding the same permanently connected to the sleeve 21 and in turn to the legs 14.

By this construction, accidental breakage of the shoulders 15 and sudden slipping of the legs 14 through the openings in the plates A and B and the housing 10 due to expansion of the spring 20, will result in a prevention of the parts being forcibly ejected and flying apart haphazardly by the spring 20 being locked to the housing 10 by the nubs or projections 26 and by the retainer being locked to the spring via the cap 24 and sleeve 21 by the nubs or projections 28 in the manner described and understood from the foregoing.

It will be understood that the locking of the spring 20 to the body 10 and to the sleeve 21 or retainer may be effected in various other manners which will readily suggest themselves to those skilled in the art, the particular method shown and described for illustration having the advantage of enabling the use of simple stamping and punching operations.

The sleeve 21 may be secured to the cap 24 in any other suitable manner, the method shown in the drawing having the advantage of involving

a minimum of parts and connecting operations.

Furthermore, the locking or anchoring of the spring to the housing and retainer, respectively, is not limited to the specific type of clamp shown in the drawing but may be used with equal advantage in any other clamp construction comprising essentially a body, a retainer slidable with respect to said body and having at least one shoulder or other clamping member at its outer end and a spring interposed between the inner end of said retainer and said body to retract said retainer and to urge said shoulder into clamping engagement with said body. In a clamp of this type, breakage of the shoulder or other clamping member would result in a sudden expansion of the spring and forcible ejection of the parts in the absence of the precautionary features proposed by the invention to hold the parts together by locking the spring to both the housing and retainer in the manner shown and described. Thus, the spreader or other complementary hole-filling element cooperating with the retainer may be constructed and mounted as shown in any of the prior art constructions and the spring may directly engage the inside of the bottom or base in accordance with the broad scope of the invention.

Accordingly, it will be evident that the invention is not limited to the specific details and constructions shown and disclosed herein for illustration, but that the underlying principle and novel thought are susceptible of numerous variations and modifications coming within the broader scope and spirit of the invention as defined in the appended claims. The specification and drawing are accordingly to be regarded in an illustrative rather than in a limiting sense.

I claim:

1. In a clamp device, a body having a base provided with an opening, a retainer slidable through said opening and having at least one shoulder at its outer end, a coil spring encircling said retainer and interposed between the inner end of said retainer and said body to normally retract said retainer and to cause said shoulder to engage said base, said body and retainer being provided with projections inter-engaging adjacent turns at the opposite ends of said spring, whereby to lock said spring to both said body and said retainer.

2. In a clamp device, a cylindrical body having a base provided with an opening, a retainer slid-able through said opening and having a pair of resilient legs provided with shoulders at the outer ends thereof, a spreader in fixed relation to said body and interposed between said legs, a coil spring interposed between the inner end of said retainer and said body to normally retract said retainer and to cause said shoulders to engage said base, said body and retainer being provided with projections inter-engaging adjacent turns at the opposite ends of said spring, whereby to lock said spring to both said body and said retainer.

3. In a clamp device, a cup-shaped body having a base provided with a central bore, a retainer slid-able through said bore and having at least one lateral projection at the outer end thereof, a coil spring interposed between the inner end of said retainer and said body to normally retract said retainer and to cause said projection to engage said base, said body being provided with in-struck internal projections inter-engaging adjacent turns at one end of said spring and said retainer having means provided with outward projections inter-engaging adjacent turns at the op-

posite end of said spring, whereby to lock said spring both to said body and said retainer.

4. In a clamp device, a cup-shaped housing having a base provided with a central bore, a retainer slid-able through said bore and having a pair of resilient legs operable towards each other and provided with shoulders at the outer ends thereof, a spreader in fixed relation to said body and interposed between said legs, a coil spring encircling said retainer and interposed between said body and the inner end of said retainer to normally retract said retainer and to cause said shoulders to engage said base, said body being provided with in-struck internal projections inter-engaging adjacent turns at one end of said spring and said retainer including means provided with projections engaging adjacent turns at the opposite end of said spring, whereby to lock said spring to both said body and said retainer.

5. In a clamp device, a cup-shaped body having a base provided with a central bore, a retainer slid-able through said bore and having at least one lateral projection at the outer end thereof, a coil spring encircling said retainer and interposed between said base and the inner end of said retainer to normally retract said retainer and to cause said projection to engage said base, a sleeve in fixed relation to the inner end of said retainer and interposed between said spring and said retainer, said body being provided with at least one inward projection inter-engaging adjacent turns at one end of said spring and said sleeve having at least one outward projection inter-engaging adjacent turns at the opposite end of said spring, whereby to lock said spring to both said body and said retainer.

6. In a clamp device, a cup-shaped body having a base provided with a central bore, a retainer slid-able through said bore and having a pair of resilient legs provided with shoulders at the outer ends thereof, a spreader in fixed relation to said body and interposed between said legs, a coil spring encircling said retainer and interposed between said base and the inner end of said retainer to normally retract said retainer and to cause said shoulders to engage the outside of said base, a sleeve in fixed relation to the inner end of said retainer and interposed between said spring and said retainer, said body being provided with at least one in-struck internal projection inter-engaging adjacent turns at one end of said spring and said sleeve being provided with at least one outward projection inter-engaging adjacent turns at the opposite end of said spring, whereby to lock said spring to both said body and said retainer.

7. In a clamp device, a cup-shaped housing having a base provided with a central bore, a retainer slid-able through said bore and having resilient legs operable towards each other and provided with shoulders at the outer ends thereof, a spreader resting against the inside of said base and having a portion interposed between said legs, a coil spring encircling said retainer having one end engaging the inner end of said retainer and arranged to maintain said spreader in bearing arrangement with said base, said spring drawing said retainer inwardly of said body to urge said shoulders spaced by said spreader against the outside of said base, a sleeve in fixed relation to the inner end of said retainer and interposed between said spring and said retainer, said body provided with at least one in-struck internal projection inter-engaging adjacent turns at one end of said spring and said sleeve being

provided with at least one outward projection engaging adjacent turns at the opposite end of said spring, whereby to lock said spring to both said body and said retainer.

8. In a clamp device, a cup-shaped housing having a base provided with a central bore, a retainer slidable through said bore and having at least one lateral projection at the outer end thereof, a cap secured to the inner end of said retainer, a sleeve in fixed relation to and having a flange adjacent to said cap, a coil spring encircling said retainer having one end engaging said flange and having its other end engaging said body to retract said retainer and to cause said projection to engage the outside of said base, said body being provided with at least one inward projection inter-engaging adjacent turns at one end of said spring and said sleeve being provided with at least one outward projection inter-engaging adjacent turns at the opposite end of said spring whereby to lock said spring to both said body and said retainer.

9. In a clamp device, a cup-shaped housing having a base provided with a central bore, a retainer slidable through said bore and having at least one lateral projection at the outer end thereof, a cap having an inwardly flaring rim and secured to the inner end of said retainer, a sleeve having a flange at one end terminating in an outwardly flaring rim engaging the rim of said cap, a coil spring encircling said retainer and interposed between said flange and said body to retract said retainer and to cause said projection to engage the outside of said base, said body being provided with at least one inward projection inter-engaging adjacent turns at one end of said spring and said sleeve being provided with at least one outward projection inter-engaging adjacent helices at the opposite end of said spring, whereby to lock said spring to both said body and said retainer.

10. In a clamp device, a cup-shaped housing having a base provided with a central bore, a retainer slidable through said bore and having at least one lateral projection at the outer end thereof, a cap secured to the inner end of said retainer, a sleeve in positive connection with said cap and having a flange adjacent to said cap, a coil spring encircling said retainer and interposed between said flange and said body to retract said retainer and to cause said projection to engage the outside of said base, said body being provided with at least one in-struck projection inter-engaging adjacent turns at one end of said spring and said sleeve having adjacent apertures and at least one connecting strap therebetween folded back upon itself to provide an outward projection inter-engaging adjacent turns at the opposite end of said spring, whereby to lock said spring to both said body and said retainer.

11. In a clamp device, a cup-shaped housing having a base provided with a central bore, a retainer slidable through said bore having a pair of resilient legs provided with shoulders at the outer ends thereof, a spreader resting against the inside of said base and having a portion interposed between said legs, a cap secured to the inner end of said retainer, a sleeve in positive connection with said cap and having a flange adjacent to said cap, a coil spring encircling said retainer having one end engaging said flange and arranged to maintain said spreader in bearing engagement with said base, said sleeve being interposed between said retainer and said spring, said body being provided with a plurality of 75

equally spaced in-struck internal projections inter-engaging adjacent turns at one end of said spring and said sleeve being provided with adjacent apertures and intervening connecting straps folded back upon themselves to provide outward projections inter-engaging adjacent turns at the opposite end of said spring, whereby to lock said spring to both said body and said retainer.

12. In a clamp device, a cup-shaped housing having a base provided with a central bore, a retainer slidable through said bore and having a pair of resilient legs provided with shoulders at the outer ends thereof, a spreader resting against the inside of said base and having a portion interposed between said legs, a cap having an inwardly flaring rim and secured to the inner end of said retainer, a sleeve having a flange at one end terminating in an outwardly flaring rim engaging the rim of said cap, a coil spring encircling said retainer and interposed between said flange and housing and arranged to maintain said spreader in bearing engagement with said base, said spring drawing said retainer inwardly of said body to urge said shoulders spaced by said spreader into clamping engagement with the outside of said base.

13. A device for temporarily clamping together perforated sheets in superposed relation comprising a body having a sheet engaging base provided with an opening, a sleeve movable relative to said body, a retainer locked in said sleeve for movement therewith, said retainer carrying means on one end projecting through said opening adapted for engagement against the underside of the sheets being clamped, a spreader for said retainer resting on the inner face of said base, and a spring having one end resting on said spreader and its other end locked to said sleeve for drawing said sleeve and retainer inwardly of said body to urge said one end of the retainer into sheet clamping engagement.

14. A device for temporarily clamping together perforated sheets in superposed relation comprising a body having a sheet engaging base provided with an opening, a hollow sleeve movable relative to said body and having a head on one end thereof, a retainer locked in said sleeve for movement therewith, said retainer including a pair of legs projecting through said opening and formed with means adapted for engagement against the underside of the sheets being clamped, a spreader for said legs, a spring interposed between the head of said sleeve and said spreader for drawing said sleeve and retainer inwardly of said body to urge the means on said legs spaced by said spreader into sheet clamping engagement, and means on said sleeve and body for locking said spring to limit its movement in one direction.

15. A device for temporarily clamping together perforated sheets in superposed relation comprising a body having a sheet engaging base provided with an opening, a sleeve movable relative to said body, a retainer locked in said sleeve for movement therewith, said retainer including means adapted for engagement against the underside of the sheets being clamped, a spring surrounding said sleeve and functioning to press said sleeve and retainer inwardly of said body to urge the means on said retainer into sheet clamping engagement, and means on said sleeve and body for locking said spring to limit its movement in one direction.
